UNITED STATES PATENT OFFICE.

OVILA D. MOREAU, OF MANVILLE, RHODE ISLAND, ASSIGNOR OF ONE-HALF TO
JOSEPH C. MAILLOUX, OF WOONSOCKET, RHODE ISLAND.

HEDDLE FRAME.

Application filed October 14, 1922. Serial No. 594,543.

To all whom it may concern:

Be it known that I, OVILA D. MOREAU, a citizen of the United States, residing at Manville, in the county of Providence and

5 State of Rhode Island, have invented certain new and useful Improvements in Heddle Frames, of which the following is a specification.

This invention relates to an improved 10 construction of heddle frame adapted to be used in looms employed in weaving goods known in the trade as fancy lenos and gauzes, but which may be also used in weaving other open-work fabrics; and the object of this invention is to provide a 15 heddle-frame of this character which is somewhat similar in its construction to a reed as the frame is provided with both dents and needles arranged in the frame 20 as desired, to weave the required pattern.

A further object of the invention is to provide a frame of this character in which dents are removably mounted therein, whereby the dents may be rearranged in 25 the frame to change the order of needle spaces and plain spaces to produce different patterns of weave in the same frame.

With these and other objects in view, the invention consists of certain novel 30 features of construction, as will be more fully described, and particularly pointed out in the appended claims.

In the accompanying drawings:

Figure 1 is a side elevation of my improved heddle frame showing the long dents 35 permanently fixed in the frame and the relatively short dents as being removably secured to the frame, and needles being located in a portion only of the spaces.

40 Figure 2 is a perspective view of one of the shorter removable dents.

Figure 3 is a perspective view showing 45 a portion of one of the frames in which the dents and needles are mounted, plain spaces being left for some of the warp threads in which no needles are mounted.

Figure 4 is an end view partly in section of my improved heddle frame.

50 Figure 5 is a perspective view of one of the needles removed.

Figure 6 is an enlarged view showing laterally projecting protuberances near the point of the needle.

It is found in practice in the weaving of such goods as fancy lenos, gauzes and the like, that very satisfactory results are obtained in the production of certain patterns of these goods by using a heddle frame of special design, for instance the running of warp threads of different colors, 60 textures or sizes along with the rest of the warp threads and to weave these design threads with a plain weave instead of the leno weave, all in the same heddle frame, and to accomplish this in a simple and effective way, I have produced a heddle frame having dents and needles therebetween, which is adapted to receive other additional removable dents to be placed 65 between the needle and its next adjacent dent to make plain spaces, the threads to be woven with the fancy weave to be passed through the needle spaces and those to be woven with the plain weave to be passed through the plain spaces provided by the use 70 of my removable dents whereby both a fancy and a plain weave may be simultaneously obtained in the same frame on the different 75 designated threads, and the following is a detailed description of one means by which 80 these results may be accomplished:—

With reference to the drawings, 10 designates the usual bars into which the ends 11 of the ordinary dents 12 are permanently secured and ordinarily in weaving plain 85 lenos the needles 13 are secured in all of the spaces between these dents, but in the construction of a heddle frame in which a plain weave is produced on some of the threads and a fancy weave on some of the 90 threads in the same frame, I have at intervals along the frame inserted an extra dent 14 between the original dent 12 and its next adjacent needle 13 thereby providing a plain space 15 or a space in which no needle 95 is set.

The auxiliary dents are preferably made shorter than the other dents and in order to retain them in the frame between the end bars 10, I have attached strips 16 and 100

17 to the inner edges of the bars 10 on opposite sides of the dents 12 so that these extra dents may be dropped into any desired place along the frame and secured 5 therein by the positioning and securing of the bars 16 and 17 and when it is desired to change the pattern of the weave, it is only necessary to remove these auxiliary dents from their places and shift or re-arrange them in the frame whereby the order 10 of the needle spaces and the plain spaces may be changed as desired, to alter the pattern of the weave and by such an arrangement the same heddle frame may be employed 15 for producing a great variety of designs or patterns of weave.

In the operation of a loom having my improved heddle frame, the warp threads which are to have a fancy weave are passed 20 through the needle spaces or spaces having a needle and the warp threads which are to be woven plain are ordinarily made of a color, size or texture different from that of the other warp threads and are passed 25 through the plain spaces or the spaces where no needles are set and then in the operation of the loom those threads in the needle spaces are woven with the leno or fancy weave and those threads in the plain 30 spaces are woven with the plain weave thus producing the pattern desired in the weave.

In the construction of a frame of this character, I preferably employ needles of the character illustrated in Figures 5 and 6, 35 which are described in my co-pending patent application Serial Number 543,277, filed March 13, 1922, the construction of which greatly facilitates the action of my improved heddle frame in the weaving of 40 lenos or gauzes of this character.

My improved heddle frame is very simple and practical in construction and effective in its operation and by its use fancy lenos or the like may be woven, and additional warp 45 threads used in the weaving of the cloth, which are passed through the plain spaces additionally formed by the insertion of my removable dents.

The foregoing description is directed 50 solely towards the construction illustrated, but I desire it to be understood that I reserve the privilege of resorting to all the mechanical changes to which the device is susceptible, the invention being defined and 55 limited only by the terms of the appended claims.

I claim:

1. A heddle frame having a multiplicity of spaced-apart dents providing spaces for the 60 reception of the warp threads, needles in said spaces each to act upon and form a fancy weave on its threads, and means in said frame whereby extra dents may be removably mounted in any desired number of spaces in 65 said frame between a needle and the next ad-

jacent dent, without removing any of the heddle parts.

2. A heddle frame, fixed spaced-apart dents therein, needles fixed at one end in the spaces between said dents to act upon 70 and form a fancy weave of the threads, and a removable dent positioned between the needle and its normally next positioned dent to provide a space in which no needle is positioned for the reception of a warp 75 thread for plain weaving.

3. A heddle frame having a multiplicity of spaced apart dents of substantially equal length, needles located in spaces between said dents to act upon and form a fancy 80 weave of the threads, and a removable dent positioned between the needle and its normally next positioned dent to provide a space in which no needle is positioned for the reception of a warp thread for plain 85 weaving.

4. A heddle frame having a multiplicity of spaced apart dents of substantially equal length, needles located in spaces between said dents to act upon and form a fancy 90 weave of the threads, a removable dent positioned between the needle and its normally next positioned dent to provide a space in which no needle is positioned for the reception of a warp thread for plain weaving, and 95 means for retaining said removable dent in position.

5. A heddle frame having a multiplicity of spaced-apart dents providing spaces for the reception of the warp threads, needles 100 in said spaces each to act upon and form a fancy weave on its thread, and means whereby an extra dent may have its opposite ends removably mounted in the upper and lower frame bars of one of said spaces between a 105 needle and its next adjacent dent to provide some needleless spaces in which warp threads to be woven plain are positioned.

6. A heddle frame having a multiplicity of spaced-apart dents providing spaces for 110 the reception of the warp threads, needles in said spaces to act upon and form a fancy weave on its threads, some of said spaces being provided each with a removable dent to form extra spaces without needles where- 115 by the threads in said spaces are woven plain, said removable dents being shorter in length than the first mentioned dents, and means for removably securing said shorter dents in the frame whereby they may be 120 readily rearranged to change the order of the needle spaces and plain spaces to vary the pattern of the weave.

7. A heddle frame having a multiplicity of spaced-apart dents providing spaces for 125 the reception of the warp threads, needles in said spaces each to act upon and form a fancy weave on its threads, some of said spaces being provided each with a removable dent to provide extra spaces without needles 130

whereby the threads in such spaces are woven plain, and a removable strip secured along the inner edge of the frame for securing the removable dents in the frame where-
5 by they may be readily arranged to change the order of the needle spaces and plain spaces to vary the pattern of the weave.

8. A heddle frame having a multiplicity

of alternate dents and needles fixed therein, and means in said frame for removably 10 mounting a dent therein between a needle and its next adjacent fixed dent, said insertable dent being of a length less than the dents fixed in the frame.

In testimony whereof I affix my signature.
OVILA D. MOREAU.
